(57) **CLAIM**

The ornamental design for a microphone, as shown and described.

DESCRIPTION

FIG. 1 is a perspective view of a microphone; FIG. 2 is a front elevational view of the microphone, a rear elevational view of the microphone being mirror-symmetrical to the front elevational view;

FIG. 3 is a top plan view of the microphone;

FIG. 4 is a bottom plan view of the microphone;

FIG. 5 is a right-side elevational view of the microphone, a left-side elevational view of the microphone being mirror-symmetrical to the right side elevational view; and,

FIG. 6 is an enlarged cross-sectional view of the microphone taken in the direction of line 6-6 of FIG. 2.

The evenly dashed broken lines in the drawings depict portions of the microphone that form no part of the claimed design. The dot-dash broken lines in the drawings depict the bounds of the claim and forms no part of the claimed design.
